UNITED STATES PATENT OFFICE.

VICTOR EHRMAN, OF LOS ANGELES, CALIFORNIA.

EDUCATIONAL TOY.

Application filed December 23, 1924. Serial No. 757,635.

To all whom it may concern:

Be it known that I, VICTOR EHRMAN, a citizen of the United States, residing at Los Angeles, in the county of Los Angeles 5 and State of California, have invented new and useful Improvements in Educational Toys, of which the following is a specification.

This invention relates to improvements in 10 educational toys.

It is an object of the invention to provide an educational toy, consisting of a plurality of keys upon which are inscribed letters, which keys actuate panels upon which are 15 mounted statuettes or images, so that the statuettes will be caused to be exposed to view upon the actuation of certain keys whereby a child may become familiar with the letters of the alphabet as associated with 20 various images.

A further object of the invention is to provide an educational toy which will be of rugged construction, easily and cheaply manufactured, and which will have a considerable amount of educational value. 25

With the foregoing and other objects in view, which will be made manifest in the following detailed description and specifically pointed out in the appended claims, reference is had to the accompanying drawings, wherein— 30

Figure 1 is a perspective view of the improved educational toy.

Fig. 2 is a vertical section taken through 35 the toy.

Fig. 3 is a side elevation of one of the panels upon which a statuette or image is mounted.

Fig. 4 is a sectional view illustrating a 40 modification of construction.

Referring to the accompanying drawings wherein similar reference characters designate similar parts throughout, the improved toy consists of a base indicated at 10, to 45 which end walls 11 and 12 are secured. Strips 13, 14, 15 and 16 are secured across the front edges of the end walls 11 and 12. Panels, as indicated at 17, are hingedly connected to the strips 13, 14 and 15 respectively, by means of fabric tapes, as indicated at 18. The fabric tapes 18 are cut adjacent their upper edges, as indicated at 50 19, so that each one of the panels 17 may hinge independently of any of the other panels. Suitable cleats 20 serve to secure the

tapes 18 to the strips 13, 14 and 15 respectively, and a suitable adhesive is employed for securing the upper portions of these tapes to their respective panels. The tapes 18 provide the hinges for the panels, although it is understood that various other hinge constructions may be substituted therefor. 60

The lower edges of the panels 17 are in line with the upper edges of the strips 13, 14 and 15 respectively. The upper edges of the panels 17 bear upon the outer face of the strips, that is, the upper edges of the panels 17 which are secured to the strip 13 bear against the face of the strip 14, and in 70 a like manner, the panels 17 secured to the strip 14 bear against the face of the strip 15. The panels 17 which are secured to the strip 15 bear against the uppermost strip 16. In this manner, each of the panels 17 is 75 slightly outwardly inclined.

A brace 21 is secured across the back edges of the end walls 11 and 12. Suitable flexible elements, generally designated at 22, are secured to the panels 17 by means of 80 suitable eyes 23. These eyes are positioned slightly above the bottoms of their respective panels 17. The flexible elements 22 may be of fine wire, cord, string, thread or the like, and are threaded through suitable eyes 85 24 mounted upon the forward face of the brace 21.

Extending between the end walls 11 and 12 there is a spindle 25 upon which keys 26 are rotatably mounted. Suitable washers 90 27 may be interposed between the keys 26 upon the spindle 25 so that each of the keys may be independently rotated with respect to each other. Adjacent the rear of each of the keys 26 there is mounted a hook 28, 95 and suitable eyes or staples 29 are fastened to the base 10 along its rearmost edge. Elastic members 30 are secured between the eyes or staples 29 and the hooks 28. These elastic members may be in the form of rubber bands, springs or equivalent construction and serve to urge the forward portion of each of the keys into its uppermost position. 100

Letters, as shown in Figure 1, are inscribed upon the forward portions of each of the keys. The flexible elements 22, after being threaded through the eyes 24, are secured to the hooks 28. A suitable roof structure, indicated at 31, may be mounted 105 110

upon the end walls 11 and 12, and if desired, suitable openings 32 may be formed therein.

In the present embodiment of the invention, a lever 33 is pivotally mounted, as indicated at 34, upon each of the end walls 11 and 12, and a suitable image or statuette, as indicated at 35, is mounted upon the free end thereof. A flexible element 36 is secured to the lever 33, and after being threaded through an eye 37, is secured to a key 26. As shown in Fig. 3, each of the panels 17 carries a small statuette, the statuette illustrated in Fig. 3 being intended to represent a duck 38.

The operation of the toy is as follows:

When a key is depressed against the action of its elastic member 30 the flexible element 22 connected to that key is loosened and this permits the corresponding panel 17 to which the flexible element is connected, to fall outwardly and downwardly. The panel 17 will naturally fall when the flexible element 22 is loosened because of its outward inclination. Each panel has its downward movement limited because of the cleats 20, as will be readily understood, so that when the key is depressed the panel actuated thereby assumes an approximately horizontal position.

As previously stated, the object of the toy is to acquaint a child with the various letters of the alphabet by associating these letters with the various statuettes displayed. For example, if the key "D" is depressed, a panel will be caused to fall and assume a horizontal position displaying a duck thereon, and in the course of time a child naturally associates the letter D with a duck. In a similar manner, if the key "H" is depressed, a horse will be displayed. The key "F" preferably actuates the lever 33 so that a flag is caused to be raised through the opening 32. In a like manner, the key bearing the letter "R" may cause a rooster mounted on a similar lever, to be thrust upwardly through its corresponding opening 32. When the keys are released elastic members 30 cause the keys to assume their original position and the flexible elements 22 to retract the panels 17 into their original positions, so as to hide the statuettes mounted thereon. When all of the keys are released, the panels cooperate to form a front wall for the building which the toy may be formed to simulate. In the present embodiment of the invention the toy is intended to simulate Noah's Ark and to display the animals therein.

From the above it is seen that an improved educational toy is provided having end walls, between which extend strips upon which are hinged panels carrying statuettes, images and the like, and that key means is provided for separately actu-

ating the various panels so as to expose the statuettes carried thereby to view.

It is understood that various changes may be made in the details of construction without departing from the spirit or scope of the invention, as defined by the appended claims.

I claim:

1. An educational toy comprising end walls, a spindle secured between said end walls, keys pivoted upon said spindle, a support secured between said end walls, panels hinged to said support, statuettes mounted upon said panels and means connecting said keys to said panels whereby when said keys are depressed said panels will be caused to assume horizontal positions so as to display the statuettes thereon.

2. An educational toy comprising end walls, a spindle secured between said end walls, keys pivoted upon said spindle, a support secured between said end walls, panels hinged to said support, statuettes mounted upon said panels and means connecting said keys to said panels whereby when said keys are depressed said panels will be caused to assume horizontal positions so as to display the statuettes thereon, and means for retracting said keys and panels into a predetermined position whereby said statuettes will assume a hidden position when said keys are released.

3. An educational toy comprising end members, strips secured to and extending between said end members, panels carrying statuettes hingedly mounted upon said strips, a spindle extending between said end members, keys pivotally mounted upon said spindle, means associated with said keys whereby one of said keys is depressed a corresponding panel will be released to expose the statuette mounted thereon, and when said key is released said panel will be moved so as to hide the statuette mounted thereon.

4. An educational toy comprising end members, strips secured to and extending between said end members, panels having statuettes mounted thereon hingedly mounted upon said strips, a spindle disposed between said end members, keys pivotally mounted upon said spindle, and flexible elements connecting said keys to said panels whereby when a key is depressed a corresponding panel will be caused to move so as to expose the statuette thereon.

5. An educational toy comprising end members, strips secured to and extending between said end members, panels having statuettes mounted thereon hingedly mounted upon said strips, a spindle disposed between said end members, keys pivotally mounted upon said spindle, and flexible elements connecting said keys to said panels whereby when a key is depressed a corresponding panel will be caused to move so as

to expose the statuette theron, and resilient means for causing said keys and panels to assume their initial positions upon release of said keys.

5 6. In an educational toy, end members, a spindle disposed between said end members, keys pivotally mounted upon said spindle, a top mounted upon said end members, an opening formed in said top, a lever pivoted upon one of said end members, a statuette mounted upon said lever, and means connecting said lever to one of said keys whereby when one of said keys is depressed the statuette mounted upon said lever will be caused to pass through said opening so as to be exposed above said top.

10 7. In an educational toy, end members, a

spindle disposed between said end members, keys pivotally mounted upon said spindle, a top mounted upon said end members, an opening formed in said top, a lever pivoted upon one of said end members, a statuette mounted upon said lever, means connecting said lever to one of said keys whereby when one of said keys is depressed the statuette 20 mounted upon said lever will be caused to pass through said opening so as to be exposed above said top, and means for retracting said statuette and said key into their original position upon release of said key. 25

15 In testimony whereof I have signed my name to this specification.

VICTOR EHRMAN.
